REFUSE COLLECTING CONTAINER

Hilding Linde, Kalmar, Sweden

Application November 24, 1936, Serial No. 112,593
In Sweden December 12, 1935

14 Claims. (Cl. 214—67)

The present invention relates to refuse collecting containers and has for its object to provide simple and efficient means for feeding the refuse into the container while simultaneously increasing its specific gravity so that the volume of the container may be more effectively utilized than would be the case if the refuse was not compressed within the container. Evidently, this is of particular importance in connection with 5 vehicular collecting containers, the invention being primarily intended for use in refuse vehicles or dust-carts.

According to the invention, improved loading means for refuse collecting containers are obtained by the provision of a rotary conveyor screw in a casing or the like which opens into the container which conveyor screw extends with its shaft preferably only partly through the container and is adapted to force the refuse out of 10 the casing into the container against the pressure created by refuse already in the container. Preferably, the pitch of this conveyor screw decreases towards the discharge opening of the casing, and in the preferred constructions the screw is directed obliquely upwards, the length 15 and general arrangement of the screw being such that its inner end as well as the discharge opening of the casing are located in the lower portion of the container, preferably at the bottom thereof. The latter may have a trough-like depression provided therein, housing the conveyor screw and sloping towards one of the walls of the container and, preferably, the casing surrounding the screw should extend into the container as 20 far as the screw itself, the casing being usually cylindrical and having a collar-like flange or extension at the upper edge of the discharge opening. At its inner end the conveyor screw should be cantilevered, whereas it may be supported at its outer end by the lower portion, preferably, of a discharging shutter swingably mounted at its top end, the preferred arrangement being such that the longitudinal direction of the conveyor screw is approximately parallel 25 to a plane perpendicular to the swinging axis of the shutter. In case of motor vehicles the screw may be driven from the motor, the connection between the motor and the screw comprising, for instance, two coupling members movable, preferably automatically, into and out of coupling engagement with one another, one of said coupling members being mounted on the vehicle proper and the other being carried by the container, preferably by the said shutter, which

may be swingable in substantially the same plane as the container.

Other features of the invention will appear from the following description and the accompanying drawings, wherein—

Figure 1 illustrates diagrammatically a motor truck with a tipping refuse collecting container according to the invention.

Figure 2 is a longitudinal section through the rear portion of the container with appendant loading means.

Figure 3 is a partial rear end view of the vehicle, cut away as indicated by the line III—III of Figure 2, and

Figure 4 shows a detailed section through the refuse feeding means.

Figure 5 is a side elevation of a dust-cart according to a second embodiment of the invention, and

Figure 6 is a sectional view taken on line VI—VI in Figure 5.

In the embodiment shown in Figures 1—4 a closed collecting container 1 is pivotally mounted, at its rear end, on the chassis 2 of a motor truck, and by means of the driving motor of said truck, in conjunction with any suitable mechanism not shown in the drawings, it may be tipped up, in the longitudinal plane of the vehicle, into the position 1¹ indicated in dotted lines in Figure 1. The rear end-wall of the container is constituted by a shutter 3 hingedly connected to the container at its upper end and adapted, at the tipping of the container, to be swung out in the same plane as the latter so as to assume the position 3¹. Any suitable mechanism may be used to bring about this opening of the shutter 3, but in the embodiment shown it mainly consists of one or more wires 4 each connected at one end to the shutter and at the other end to the chassis 2, and each mounted on a segmental guide 5 at the top of the shutter and on upper and lower guide rolls 6 at the front end of the container whereby the shutter is automatically swung outwardly when the container is being tipped.

Provided in the rear portion of the bottom of the container is a trough-like depression 7, sloping rearwardly and located between the longitudinal carriers 2 of the chassis. When the shutter 3 is in its closed position this depression is occupied by the lower portion of a substantially cylindrical casing or mantle 8 for a conveyor screw 9 which parts are both supported by the shutter 3. The screw 9 is fixed to a shaft 10 which passes through the shutter and

is journalled in a bearing 11, mounted out-side the shutter, as well as in an axial bearing 12 supported by a hood 13 secured to the outer side of the shutter. In the embodiment shown, the discharge opening 23 of the mantle 8 is located approximately in the same plane as the adjacent end of the conveyor screw, and is provided at its top edge, at least, with a conical collar 24 diverging from the axis of the screw, the purpose 10 of this structure being to protect the cantilevered screw against lateral strain from the material collected in the container. This collar may be formed integral with the mantle or it may consist of a plate or flange fixed thereto. To 15 the top of or laterally of the rear portion of the mantle and located at some distance from the discharge opening thereof is connected a loading chute 25, extending through the shutter 3 and having a loading inlet outside the same. 20 Preferably, this inlet is provided with a device enabling a dustless discharge of dustbins, which device may or may not be known per se. The device indicated in Figures 2 and 3 comprises a loading shutter 26 mounted to swing about its lower edge and having an opening 27 provided therein, and a cover 28 hingedly connected to the shutter 26 and covering the opening 27 when the shutter 26 occupies a substantially vertical position. 25 30 Preferably, the area of the mantle discharge opening is substantially, in the embodiment shown more than 50 per cent, larger than the cross-area of the conveyor screw, and in some cases it will also be suitable to arrange the screw eccentrically within the casing or mantle. In Figure 3 the eccentricity is denoted by e , the screw being located nearest to the one of the opposite casing walls adjoining the walls of the chute, towards which the peripheral screw portions move, upon rotation of the screw in the direction of the arrow, from a position opposite the chute opening. The shape of the screw is such that the pitch s decreases towards the inner end of the screw, and the screw generatrix G 40 forms an acute angle α with the axial direction of the casing. Housed by the hood 13 is a worm wheel 14 (indicated by dotted lines in Figure 4) fixed to the shaft 10 and meshing with a worm 45 15 on a shaft 16, connected by means of a bevel gear 17, 18 to a shaft 19, the latter and the shaft 16 being both carried by the shutter 3. In the closed position of the latter the shaft 19 is co-axial with a shaft 20 journalled on the chassis 2, and is connected thereto by means of a claw- 50 55 coupling 21, 22, one member of which (according to Figure 4 the member 22, mounted on shaft 20) may be urged by a spring towards the other member. The shaft 20 may be connected to the ordinary drive-motor of the vehicle or with any other source of power. When the shutter 3 together with the parts carried thereby is swung out from the container, the coupling members 21, 22 are disconnected. At the return motion 60 65 of the container and the shutter they are automatically brought back into coupling engagement, whereupon the shutter 3 may be locked to the container by some suitable means not shown in the drawings.

When a dustbin 29 is emptied through the 70 shutter opening 27 the refuse falls, through chute 25, into the portion of the casing 8 located beneath the chute. When the conveyor screw is rotated in the direction of the arrow by the driving means 14—22, the refuse is forced towards 75 the discharge opening of the casing and is forced

into the container against the pressure created by refuse previously existent therein. Apparently, this pressure increases with the refuse contents of the container, so that a compression of the refuse takes place during the loading operation. Since refuse material is highly compressible, its specific gravity is thereby increased to a considerable extent so that by far more refuse may be fed into the container than would otherwise be the case. The decreasing pitch of the conveyor screw obviously causes some compression of the refuse before the latter enters the container. 5

In order to effect the compression aimed at the conveyor screw need not necessarily, as in the embodiment above described, be arranged at the bottom end of a swinging discharge shutter mounted on the container. Instead the screw conveyor may, for instance, be stationarily mounted in or at one end of the container. Such embodiment is shown in Figures 5 and 6, wherein numeral 40 denotes a collecting container having a rear discharge shutter and being pivotally mounted at its rear end, not shown in the drawings, on the chassis 41 of a motor truck, the driving motor of which is adapted, by means of a screw device indicated diagrammatically at 42, to tip the container in the longitudinal plane of the vehicle. In this embodiment also the conveyor screw 43, which is directed towards the 30 interior of the container, is arranged in a trough-like depression or recess 44 in the bottom of the container and may be cantilevered in the same way as in the embodiment previously described. The driving means may be similar in principle 35 but may comprise also a pair of gear wheels which are mounted respectively on the container and the chassis so as to be brought into and out of engagement when the container assumes or is raised from its normal horizontal position. The recess 44 slopes towards the front end-wall of the container and is arranged laterally of the chassis 41 and, preferably, is adapted to form part of a casing 45 housing the conveyor screw 43, the discharge opening 46 of the casing being 45 inclined upwards and provided with a collar 47 at its upper edge. At some distance from its discharge opening, the casing 45 is surmounted by a chute 48 arranged within the container and having a loading opening 49 provided in the side-wall of the container. The said opening may be provided with a device for dustless discharge of the kind above referred to. The conveyor screw may be constructed in the same manner as the screw 9, and the manner in which the 55 refuse is fed into the container will also be similar to that previously described.

Various other embodiments of the invention are possible and, obviously, the embodiments shown may be modified in different respects 60 without departing from the idea of the invention. Thus, it is not absolutely necessary that the conveyor screw generatrix forms an acute angle with the axis of the screw, for the angle in question may also be a right one and, moreover, the 65 generatrix may be a curved line. In embodiments, wherein the collecting container is adapted to be emptied by tipping and wherein the screw is carried by said container and connected with some external source of power, the 70 said driving connection need not necessarily be mechanical. In lieu thereof it may be electrical or hydraulical, the screw being driven by an electric or hydraulic motor supported by the container and, by means of suitably mounted con- 75

nections, fed from a generator or pump, respectively, which, in case of powerdriven refuse vehicles, may be driven by the drive motor of the vehicle. The driving connections in question may 5 be so arranged that they need not be interrupted or broken upon tipping of the container.

This also applies to a mechanical connection which, for this purpose, may be lead through the swinging centre of the container and, where 10 the screw is carried by a swingable discharge shutter, also through the swinging centre of said shutter. In such embodiments, on the other hand, where the driving connection is interrupted or broken at the tipping of the container, the 15 same need not necessarily comprise an automatic coupling, as was the case in the embodiment shown in Figures 1-4. Since the driving connection must be broken only at the time the container is being emptied, a manually operated 20 coupling may, in certain cases, be employed without considerable inconvenience. Although in the embodiment shown in Figures 1-4 the casing for the conveyor screw is constituted by a continuous 25 sheet metal mantle 8 carried by the movable shutter 3, it will also be possible to omit the lower portion of the mantle, leaving its function to be performed, for instance, by the trough-like depression 7. In such case the peripheral extent 30 of the latter should, preferably, be made somewhat more than 180° and that of the top portion be shortened correspondingly so that the lower position of the casing thus formed will not impede movement of the top portion when the shutter is to be opened. This object is attained also 35 in case the lower portion and the top portion are slightly displaced laterally.

Although the invention is primarily adaptable for use in connection with dustcarts, etc., it may 40 evidently be used to advantage also in collecting and transport containers for loose materials other than refuse, provided said material is relatively compressible.

What I claim is:

1. In a refuse collecting container mounted on 45 a motor vehicle having a chassis, the combination with a casing having a discharge opening into the container, of a rotary conveyor screw adapted to force the refuse out of said casing and into the container against the pressure created by refuse already in the container, said conveyor screw having a shaft, said screw including its shaft being sufficiently short to leave a free distribution space between the shaft end, in the feeding direction, and the opposite container 50 wall, and means for establishing a driving connection between the vehicle motor and the other end of the conveyor screw, said driving connection comprising two coupling members, one of which is carried by the container and the other by the vehicle chassis, and said coupling members being movable into and out of coupling engagement with one another.

2. In a refuse collecting container having a swingable discharge closure, the combination 55 with a casing which opens into the container, of a rotary conveyor screw, a cantilever mounting for the end portion of the conveyor screw located nearest to the discharge opening of the casing, said screw being adapted to force the refuse out 60 of said casing into the container against the pressure created by refuse already in the container, said conveyor screw and said casing being carried by the swingable closure.

3. A refuse collecting container as claimed in 75 claim 2, the conveyor screw being arranged in

side the closure, and driving means for the screw outside the closure.

4. A refuse vehicle, comprising in combination, a vehicle chassis, a closed collecting container carried by said chassis and mounted to 5 swing about a substantially horizontal axis at the rear end thereof, a rotary conveyor screw having a shaft and being stationarily mounted in the opposite end of the container, and an open-ended casing for said conveyor screw, said screw, 10 including its shaft, being of a length sufficiently short to leave a free distribution space between the shaft end, in the feeding direction, and the rear end wall of the container.

5. In a refuse collecting container, the combination 15 with a casing having a discharge opening into the container, of a rotary conveyor screw adapted to force the refuse out of said casing and into the container against the pressure created by refuse already in the container, said conveyor screw, including a shaft, being of a length sufficiently short to leave a free distribution space between the end of the screw including the shaft thereof and the container wall in the feeding direction, the pitch of said conveyor screw decreasing 20 towards the discharge opening of the casing, and means for driving the opposite end of the conveyor screw.

6. In a refuse collecting container, the combination 25 with a casing having a discharge opening into the container, of a rotary conveyor screw extending through said casing and adapted to force the refuse out of said discharge opening into the container, said conveyor screw having a shaft, the inner end of said shaft being located 30 substantially in the center of said discharge opening, and said casing, at the upper edge of its discharge opening, having a collar-like flange diverging from the axis of the conveyor screw.

7. In a refuse collecting container, the combination 35 with a casing having a discharge opening into the container, of a rotary conveyor screw within said casing and adapted to force the refuse out of said discharge opening into the container against the pressure created by refuse already in the container, and a cantilever mounting for the inner end portion of said conveyor screw.

8. In a refuse collecting container, the combination 40 with a substantially cylindrical casing 50 having a discharge opening into the container, of a rotary conveyor screw extending through said casing and adapted to force the refuse out of said casing and into the container against the pressure created by refuse already in the container, and the said screw being eccentrically mounted relatively to the said casing.

9. A refuse collecting container as claimed in 55 claim 8, and wherein a portion of the casing located at a distance from the discharge opening, is connected above to a loading chute, the conveyor screw being located nearest to the one of two opposite casing walls adjoining the chute, towards which the peripheral screw portions move from a position opposite the chute.

10. In a refuse collecting container, the combination 60 with a casing having a discharge opening into the container, of a rotary conveyor screw adapted to force the refuse out of said casing and into the container against the pressure 65 created by refuse already in the container, said conveyor screw, including a shaft, being of a length sufficiently short to leave a free distribution space between the end of the screw including the shaft thereof and the container wall located in the feeding direction, the conveyor screw 70

generatrix forming an acute angle with the axial direction of the screw towards the discharge opening of the casing, and means for driving the opposite end of the conveyor screw.

- 5 11. A refuse vehicle, comprising in combination, a motor vehicle, a collecting container swingably mounted on said motor vehicle, a discharge shutter constituting one of the walls of the container and hingedly connected thereto
- 10 at its top portion, the shutter and the container being mounted to swing in substantially the same plane, a casing opening into the container, a rotary conveyor screw carried by said shutter and adapted to force the refuse out of said casing and into the container against the pressure created by refuse already in the container, and a driving connection between the vehicle motor and the conveyor screw, said driving connection comprising two coupling members, one of which is carried by the shutter whereas the other is mounted on the vehicle.
- 15 12. A refuse vehicle as claimed in claim 4, and the container having a floor provided with a trough-like depression laterally of the vehicle chassis carrying the container, the conveyor screw being located in said depression.
- 20
- 25

13. In a refuse collecting container, the combination with a casing having a discharge opening into the container, of a rotary conveyor screw within said casing adapted to force the refuse out of said discharge opening and into the container, and a swingable discharge closure of the container, said casing comprising an upper portion carried by said closure and a lower portion constituted by a trough-like depression of the bottom of the container, and said conveyor screw being mounted on said closure swingable together with said closure and the upper portion of the casing.

14. A refuse vehicle comprising a vehicle chassis, a body carried by said chassis, said body having a refuse receiving device in its fore end and a refuse collecting container in its rear portion, and a rearwardly directed rotary conveyor screw located near the bottom of the body with its fore portion below said refuse receiving device to feed the refuse into the refuse collecting container, and driving means connecting the fore end of said screw with the motor of the vehicle for driving said conveyor screw, the rear end of said screw having a cantilever mounting.

HILDING LINDE.
